(74) Attorney, Agent, or Firm—Hugh D. Jaeger

(57) **CLAIM**

The ornamental design for an electronic sign enclosure having a rail, as shown.

DESCRIPTION

FIG. 1 illustrates a front view thereof;
FIG. 2 illustrates a back view thereof;
FIG. 3 illustrates a left side view thereof;
FIG. 4 illustrates a right side view thereof;
FIG. 5 illustrates a top view thereof;
FIG. 6 illustrates a bottom view thereof;
FIG. 7 illustrates a front isometric view thereof; and,
FIG. 8 illustrates a rear isometric view thereof.
